UNITED STATES PATENT OFFICE.

WILLIAM G. GROESBECK AND GEORGE S. RADFORD, OF BOSTON,
MASSACHUSETTS.

MEANS FOR CONTROLLING AUTOMOBILES.

No. 844,863.

Specification of Letters Patent.

Patented Feb. 19, 1907.

Application filed July 18 1906. Serial No. 326,753.

To all whom it may concern:

Be it known that we, WILLIAM G. GROESBECK and GEORGE S. RADFORD, citizens of the United States, residing at Boston, in the county of Suffolk and State of Massachusetts, have invented certain new and useful Improvements in Means for Controlling Automobiles; and we do hereby declare the following to be a full, clear, and exact description of the invention, such as will enable others skilled in the art to which it appertains to make and use the same.

Our invention relates to improvements in means for controlling automobiles; and the object of our invention is to provide means whereby the driving-gear may be disengaged from the engine and the speed of the drive varied or reversed, all by the movement of a single lever, and also to provide means whereby by the movement of a single lever the driving-gear may be disengaged from the engine and the emergency-brake applied.

A further object is to provide means whereby the throttle-valve may be operated in connection with one of said levers.

With these objects in view our invention consists in the construction and combinations of parts, as hereinafter described and claimed.

In the accompanying drawings, Figure 1 is a top plan view of a portion of an automobile, showing our invention applied thereto. Fig. 2 is a side view showing the means for governing the transmitting mechanism. Fig. 3 is a side view showing the connections between the operating-levers and the gear-changing mechanisms. Figs. 4 and 5 are perspective views of the mechanism for governing the throttle-valve. Fig. 6 is a cross-sectional view showing the coupling connecting the two portions of the driving-shaft. Fig. 7 is a cross-section on the line 7-7 of Fig. 3, and Fig. 8 is a cross-section of the mechanism for disengaging the parts of the friction-drive mechanism.

a represents the ordinary iron frame; *b*, the driving-shaft; *c*, the fly-wheel; *d*, the engine having the exhaust *e* and inlet-valves *f*, and *g* represents the throttle-valve governing the *e* inlet of carbureted air to the cylinders. The driving-shaft is made in two sections, as shown in Fig. 6, the part *b* terminating in a squared end *h*, which engages a square opening in one member *i* of a coupling, the other

member *j* of which is fastened to the other portion *k* of the driving-shaft.

The parts *i* and *j* are connected together by means of bolts *m*, fastened to the member *j* and passing loosely through holes *n* in the member *i*. Springs *o* normally keep the members *i* and *j* in the position shown in Fig. 6; but space is afforded whereby the part *k* of the shaft may be moved toward the part *b*. The part *k* of the shaft is provided with a collar *p*, fastened thereto and best shown in Fig. 8, and loosely mounted on said shaft *k* are two cam members *q* and *r*, each provided with teeth, such as *s*, which intermesh with each other. The part *r* is attached to or made integral with the cross-beam *t*, forming a part of the frame of the machine. The shaft *h* terminates in a wheel *u*, which forms one member of a friction-gearing. This wheel is preferably covered on one face with a covering of leather *v*.

The wheel *u* is adapted to engage the friction-wheel *w*, mounted on the shaft *x*. The wheel *w* is slidably mounted on the shaft *x*, but is splined thereto, so that the wheel and shaft revolve together. *y* represents sprocket-chains, by which the motion is transmitted from the shaft *x* to the driving-axle.

It is evident from the construction described that a movement of the member *q* will, by means of the teeth *s*, force the member *g* to the right, as shown in Figs. 1 and 8, against the tension of the springs *o*, thereby disengaging the friction-wheels *u* and *w*, so that the motion of the engine will not be transmitted to the shaft *x*. After this disengagement the wheel *w* may be easily shifted, by means hereinafter described, so as to vary or reverse the speed.

The member *q* is shifted by the following means: To the top of this member is attached a pin 1, and a link 2 or wire-rope connection runs from said pin and is pivoted to the lower end of the lever 3, which lever is pivoted at 4 on a sleeve 5, mounted in the frame of the machine. The lever 3, therefore, is capable of two motions at right angles to each other, the first motion moving the link 2 or wire-rope connection, and thereby the member *q*, thus disengaging the wheels *u* and *w* from each other, and then is capable of another motion in a direction at right angles to the former motion, whereby the sleeve 5 is rocked and the wheel *w* adjusted along the

face of the wheel u for the purpose of changing the speed or reversing the driving-gear. This shifting of the wheel w is accomplished by the following means:

5 Pivoted to the sleeve 5 is a depending arm 6, and to the lower end of this arm is pivoted a link 7, which link is at the other end pivoted to one end of a bell-crank lever 8, which is pivoted at 9 on the frame of the machine, the other end of said lever terminating in a fork 10, which engages a sleeve 11, made integral with the wheel w .

From the construction described it is obvious that a motion of the lever 3 in such a direction as to rock the sleeve 5 will also move the wheel w across the face of the wheel u . Thus by means of a single lever the parts of the driving-gear may be disengaged from each other and the gearing shifted.

20 12 represents a double curved rack, which is provided with a series of teeth 13, with which the lever 3 is adapted to engage. The lever 3 is also provided with a catch 14, operated by a spring 15, and a hand-clip 16 in the usual way, so that it will hold the lever 3 in any one of several possible positions.

When it is desired to change or to reverse the speed, the lever 3 is shifted from the position shown in Fig. 3, the hand-clip 16 being first operated to disengage the stop from the teeth. This movement to the right disengages the lever 3 from the teeth 13 and at the same time by means of the connections already described moves away the wheel u 35 from the wheel w . By moving the lever 3 back and forth the wheel w may then be adjusted to different positions on the wheel u , thus varying the speed or reversing the gear. When the desired adjustment has been attained, the lever 3 is moved to the left, thus causing it to engage with the teeth 13, and the hand-clip 16 released, thus locking the lever in the adjusted position. Means are also provided whereby the setting of the emergency-brake will also disengage the wheel u 45 from the wheel w . It is designed, of course, to use the ordinary foot-brake, (not shown;) but it often happens that an emergency-brake is desirable.

50 17 represents the emergency-brake lever, which is connected by means (not shown) to any suitable brake. (Not shown.) The emergency-lever 17 is pivoted at 18 on a shaft 19, which passes through the frame of the machine. The emergency-brake is therefore capable of two motions, a rocking motion on the shaft 19 and another motion at right angles thereto, by means of which the emergency-brake is applied. To the lower 55 end of the brake-lever 17 is attached a link 20 or wire-rope connection, the other end of which passes over the pin 1. The link 20 is provided with a slot 21, so that the member g may be operated without the operation of 60 the emergency-brake, if desired.

The rack 12 is provided with a series of teeth 22, and the lever 17 is provided with a stop 23, a link 24, a spring 25, and a hand-clip 26 of the usual construction. In the operation of this emergency-brake lever the hand-clip 26 is operated, disengaging the stop 23 from the teeth 22, the lever 17 moved to the right from the position shown in Fig. 3, thus disengaging the wheel w from the wheel u , and the brake-lever 17 is then pushed forward, setting the emergency-brake by any suitable means. Thus it will be seen that before the emergency-brake is set the engine is disengaged from the driving-gear, a result greatly to be desired. Thus by the movement of a single lever the engine is disengaged from the driving-gear and the emergency-brake set.

The construction described covers the application of our invention to a friction-drive type of car. It is evident from this construction that it is equally applicable to any gear-driven car. For such a car the application of our invention would be precisely the same as shown in the drawings, except that instead of transmitting motion to the shaft k through the links 2 and 20 and the members r and q , whereby the friction-wheels u and w are separated, the movement of the links 2 and 20 and the consequent operation of the members r and q could be applied to separate the parts of the friction-gear ordinarily provided in gear-driven cars, and thus cut out the engine from the driven shaft, substantially as is now done by the foot-pedal in ordinary use. Our device may be used with either type of car in conjunction with or as a substitute for the foot-pedal. Means are also provided on the emergency-brake lever for operating the throttle-valve. To this throttle-valve g is connected a link 27, the other end of said link being connected to the downwardly-projecting portion 28 of a crank 29, which passes through the shaft 19. This crank has an upwardly-extending sector-shaped portion 31, having a rack 32 along its upper edge. With the rack 32 meshes a pinion 33, carried on the end of a shaft 34, which is provided at its upper end with a milled end 35. The shaft 34 passes centrally down through the top of said lever 17 in convenient position to be reached by the operator.

Having thus described our invention, what we claim as new, and desire to secure by Letters Patent, is—

1. In an automobile, the combination of an engine, a two-part driving-shaft coupled to said engine, a friction-wheel carried by one of the parts of said driving-shaft, a driven shaft provided with a friction-wheel for engaging with said first-named friction-wheel, cam members through which one part of said shaft passes, one of said cam members being carried by the frame of the machine, a lever for operating the other of said

cam members, thereby disengaging said friction-wheels from each other, and connections whereby the movement of said lever in a certain direction shifts one of said friction-wheels relatively to the other, substantially as described.

2. In an automobile, the combination of an engine, a two-part driving-shaft coupled thereto, a spring-controlled coupling connecting the parts of said driving-shaft, a friction-wheel carried by one end of said driving-shaft, a driven shaft, a friction-wheel splined on said driven shaft, but movable thereon, cam members through which one part of said shaft loosely passes, an operating-lever, connections between said operating-lever and one of said cam members, and connections between said lever and the friction-wheel on the driven shaft, substantially as described.

3. In an automobile, the combination of an engine, a two-part driving-shaft coupled thereto, a friction-wheel carried at one end of said shaft, a driven shaft, a friction-wheel mounted on said driven shaft and normally in contact with said first-named friction-wheel, a two-part cam through which said driving-shaft loosely passes, an emergency-brake lever, and connections between said emergency-brake lever and one part of said cam, whereby by the movement of said lever the friction-wheels may be disengaged from each other, and by an additional movement of said lever the emergency-brake may be applied, substantially as described.

4. In an automobile, the combination of an engine, a two-part shaft coupled thereto, a friction-wheel secured on one end of said shaft, a driven shaft having a friction-wheel slidably mounted thereon and normally in contact with said first-named friction-wheel, a two-part cam, one of the members of which is fixed and the other movable, through which cam said shaft loosely passes, a lever for operating the movable member of said cam, thereby disengaging said friction-wheels, an emergency-brake lever, and a link connected with said emergency-brake lever and said movable cam member so that said member may be moved either by the operating-lever when it is desired to vary or reverse the speed or by the emergency-brake

lever to disengage the parts of the driving-gear from each other before the emergency-brake is applied, substantially as described. 55

5. In an automobile, the combination of an engine, a throttle-valve therefor, a two-part driving-shaft coupled to said engine, said shaft being provided at one end with a friction-wheel, a driven shaft provided with 60 a friction-wheel slidably mounted thereon, a cam having one fixed member and one movable member through which said driving-shaft loosely passes, an emergency-brake lever, connections between the movable 65 member of said cam and said emergency-brake lever, and means carried by said emergency-brake lever for governing said throttle-valve, substantially as described.

6. In an automobile, the combination of 70 an engine, a two-part driving-shaft coupled thereto, one of said parts being movable in relation to the other, a friction-wheel carried at the end of said shaft, a two-part cam one member of which is fixed and the other 75 movable, through which cam said driving-shaft loosely passes, a driven shaft having a friction-wheel slidably mounted thereon, an operating-lever, means whereby the movement of said lever in two directions first disengages said friction-wheels from each other and then shifts one of them relatively to the other, and means for locking said lever in any one of several positions, substantially as described. 80

7. In an automobile, the combination of 85 an engine, a throttle-valve therefor, an emergency-brake lever, means for locking said lever, and means for operating the throttle-valve carried by said emergency-brake lever, and including a rod provided with a milled head and a pinion, a crank provided with a sector-shaped gear meshing with said pinion, and a connection between said crank and said throttle-valve, substantially as described. 90

In testimony whereof we affix our signatures in presence of two witnesses.
